MULTISTAGE DEAERATING AND REHEATING HOT WELL FOR STEAM CONDENSERS

Alfred D. Karr, Newark, N. J., assignor to Ingersoll-Rand Company, New York, N. Y., a corporation of New Jersey

Application June 18, 1948, Serial No. 33,868

1 Claim. (Cl. 257—43)

1

This invention relates to heat interchange devices, and more particularly to a condensate heater for a steam condenser of the type having a hot well at its base for the reception of the condensate.

One object of the invention is to assure a high temperature of the condensate immediately prior to its removal from the hot well, and

Other objects are to salvage the heat contained in the drips flowing from auxiliary apparatus, heaters for example, at higher pressures and temperatures than exist in the condenser and deliver it to the condensate, to effect the maximum deaeration of the condensate, and to obtain these advantages without necessitating the addition of other pieces of equipment to the condensing apparatus.

Other objects will be in part obvious and in part pointed out hereinafter.

In the drawings accompanying this specification and in which similar reference numerals refer to similar parts,

Figure 1 is an elevation, in section, taken through an intermediate portion of the condenser, and

Figure 2 is a side elevation, partly broken away, taken through Figure 1 on the line 2—2.

Referring more particularly to the drawings, the condenser, designated 28, comprises a casing 21 having an inlet 22 at its upper end for the entrance of exhaust steam and an outlet 23 at its lower end for the escape of condensate into a hot well 24 extending part way along the lower portion of the casing 21. The casing 21 contains a group of horizontally disposed cooling water conveying tubes 25 that communicate, in a well known manner, with headers 26 and 27 at the ends of the casing 21.

As is well known, in surface condensers having tube nests of considerable depth, there is a material drop in pressure between the inlet and outlet openings and consequently a corresponding decrease of temperature in the lower portion of the condenser which results in a lowering of the temperature of the condensate. For example, in the condenser embodying the invention and with an inlet pressure corresponding to 2.00 inches mercury and a temperature of 101.14° F., the pressure at the outlet 23 corresponds to 1.90 inches mercury and a temperature of 99.44° F. This, as will be readily apparent, represents a material lowering of the temperature of the condensate and in order to restore the heat thus lost the casing is provided with a partition 28 shown as cooperating with the side wall of the casing

2 to define a passage 29 which opens at one end into the upper region of the condenser and at its other end into the hot well to convey thereto steam directly from the inlet 22.

In view of the fact that the same differential will then exist between the pressures in the hot well and the lower region of the condenser that exists between the pressures in the upper and lower portions of the condenser it is essential that means be provided to restrain the steam in the hot well from flowing through the outlet 23 into the condenser. To this end the casing 21 is provided with a nozzle 30 that depends from the bounding surfaces of the outlet 23 and extends into a trough 31 so that its outlet end portion will be well immersed in the condensate in the trough, and a column of condensate will stand within the nozzle 30 to an elevation corresponding to the difference between the pressures in the hot well and at the outlet 23 to assist in maintaining a liquid seal at the nozzle 30.

The trough 31 extends endwise of and is of less width than the hot well so that steam may circulate freely through the hot well and around the trough. In the side walls 32 of the trough, preferably near their upper edges, are rows of apertures 33 for the flow of condensate from the trough into the hot well in the form of jets so that a maximum area of the condensate will be exposed to the steam circulating through the hot well. The upper portion of the hot well is vented to the lower zone of the condenser, as through a tube, or tubes, 34 the flow area of which is so chosen that it will provide an outlet for the uncondensable gases liberated from the jets of condensate and for any excess steam in the hot well without lowering the pressure within the hot well below the desired value.

Means are provided for still further increasing the temperature of the condensate and to effect its deaeration. To this end the casing is provided with a pair of horizontal walls 35 to divide the hot well 24 into upper and lower compartments 36 and 37, respectively. The walls are shown formed integrally with the casing. They lie in the same horizontal plane and their inner opposed edges are suitably spaced with respect to each other to define an outlet 38 for the compartment 36 and have walls 39 depending therefrom into a trough 40, in the compartment 37, so that the condensate in the trough 40 and between the walls 39 will serve as a liquid seal between the compartments. The trough 40 is shown as being a replica of the trough 31. It is preferably supported at its ends by the casing 21, in

spaced relation with the bottom of the compartment 37, and has the apertures 33 along its sides to cause the condensate to enter the hot well in jet form.

The heating medium serving to thus further increase the temperature of the condensate prior to its passage from the compartment 37, through the usual discharge conduit 41, is introduced into the compartment 37 through a port 42 in the casing 21. It is conveyed to the port 42 by a conduit 43 which may lead from a source of higher temperature and pressure, as for example, an intermediate stage of a turbine discharging into the condenser, or a heater, the drip from which should be of a greater pressure than that in the compartment and of a temperature, and of course of a sufficient quantity, to create a pressure within the compartment 37 corresponding to say, 2.20 inches of mercury and a temperature of 104.34° F., so that a higher pressure and temperature will exist in the compartment 37 than in the compartment 36. If, on the other hand, steam serves as the heating medium, it must enter the compartment 37 at a pressure of at least the same value as that in the said compartment and in sufficient quantity to heat the condensate spilling from the trough 40 to the desired temperature.

The uncondensable gases thus liberated from the condensate in the compartment 37 may escape through a tube, or tubes, 44 into the compartment 36, whence they will pass through the tubes 34 into the condenser to flow over the lower-most tubes 25 and be withdrawn, by well-known evacuating means (not shown), through passages 45 opening into the nozzle 30 and communicating with a discharge conduit 46. In this connection, it should be understood that the tube 44 is also of such flow area that, in operation, it will provide an ample outlet for the uncondensable gases and excess steam from the compartment 37 and will, at the same time, maintain the desired differential between the pressures in the compartments 36 and 37.

In the operation of the condenser, the steam entering the inlet opening 22 and passing downwardly over the cool surfaces of the tube 25 will be condensed, and the condensate thus formed will pass through the nozzle 30 into the trough 31, thence through the apertures 33 into the compartment 36 in the form of jets. At the same time, steam at discharge temperature and pressure will flow through the passage 29 into the compartment 36 into intimate contact with the jets of condensate issuing from the trough 31 and is condensed by and its heat is transferred to the condensate.

The gases liberated by this increase in the temperature of the condensate will escape through the tubes 34 into the condenser for removal by the evacuating apparatus, and the heated condensate will flow along the walls 35 and through the outlet 38 into the trough, thence through the apertures 33 into the compartment 37 as jets for exposure to the heat of the fluid medium entering the compartment 37 through the port 42. The exposure of the condensate to this hot medium will cause the further degasification and heating of the condensate prior to its passage through the discharge conduit 41 to a boiler. The uncondensable gases released by thus further heating the condensate will escape from the compartment 37 through the tubes 44 into the com-

partment 36 and pass therefrom through the channels connecting the compartment 36 with the evacuating apparatus.

From the foregoing description, it will be obvious to those skilled in the art that, by subjecting the condensate repeatedly to a heating medium capable of bringing it to a boiling point, the condensate may be substantially freed of dissolved gases found to have a corrosive effect upon the surfaces of boiler tubes and the like.

While I have shown my invention in a form capable of subjecting the condensate to only two steps of heating and deaeration, it is to be understood that I do not intend it to be so limited, and that the invention is susceptible of further modification, as for example by the addition of one or more deaeration compartments, without departing from its spirit or the scope of the claims.

I claim:

In an apparatus of the character described, a condenser, a hot well for the condenser having an upper compartment and a lower compartment, walls in said well for dividing the well into said compartments, a trough in the upper compartment, an outlet for the condenser to allow the flow of condensate to the hot well said outlet having a side depending from the condenser into the trough in the upper compartment below the overflow point so as to form a liquid seal between the condenser and the upper compartment, a trough in the lower compartment, an outlet for the upper compartment to allow the flow of condensate to the lower compartment said outlet having sides depending from said walls and extending into the trough in the lower compartment below the overflow point so as to form a liquid seal between the upper and lower compartments, a plurality of apertures in the troughs to allow the condensate in the liquid seals to flow into the respective compartments, an inlet in one side of the upper compartment for introducing steam from the condenser to increase the temperature of the condensate, an outlet in the opposite side of the upper compartment to allow uncondensable gases to escape from the upper compartment to the condenser, an inlet opening in one side of the lower compartment for the introduction of a hot fluid medium from an external source to further increase the temperature of the condensate, and an outlet in the opposite side of the lower compartment to allow uncondensable gases to escape from the lower compartment to the upper compartment.
